UNITED STATES PATENT OFFICE

JOHN W. FORSYTHE, OF WILKINSBURG, PENNSYLVANIA

SKIMMER

Application filed October 17, 1930. Serial No. 489,416.

This invention relates to a method of and apparatus for skimming or removing surface impurities from molten metals such as iron and steel, and the primary object in view is to provide a convenient and effective method and means whereby impurities such as slag, kish and the like that may be floating on the surface of the metal in a ladle or analogous container prior to pouring may be retained in the ladle after the pouring operation and dumped into a separate container or disposed of in any desired manner.

The method consists, essentially, in pouring the molten metal from a container through a restricted outlet, and interposing an obstruction to the top surface portion of the metal, while pouring, to engage and retain the impurities in the container.

In the drawings:

20 Figure 1 is a top plan view of the improved skimming apparatus in operative position on a pouring ladle.

Figure 2 is a central sectional elevation thereof.

25 Figure 3 is a view in side elevation, showing the ladle with the skimmer in position thereon in extreme tilted position.

Figures 4, 5 and 6 are detail sectional views taken, respectively, on the lines IV—IV, 80 V—V, and VI—VI of Figure 2.

The reference numeral 5 designates a top pouring ladle of the usual type, having pouring spouts 6 and 6', and trunnions 7, by means of which it may be hooked and suspended from an overhead crane, the crane hook being indicated at 8, Fig. 3.

The preferred type of skimming apparatus used in carrying out the present method consists essentially of a skimmer plate 9, which may be formed of suitable heat-resisting material or made of cast metal and lined with refractory material, said plate being formed with a cored-out portion 10 terminating on each side of the plate in hubs 12 provided with set screws 13, a supporting shaft 14 being passed through the hubs and adjustably secured thereto by said screws, the opposite extremities of the shaft resting on the top of the ladle 5 when the skimmer is positioned thereon. The length of the shaft is such as

to accommodate ladles of varying diameters.

The working edge of the skimmer plate 9 is formed with a retaining portion or is flanged as at 15 and said edge is contoured to conform to the contour of the inner refractory wall or lining of the ladle adjacent the spouts 6, 6' to thus enable it to fit closely to said wall.

55 The shaft 14 is formed with keyways and mounted in holders 16, which are formed with cooperating key seats, said holders being suitably secured to side frame members or beams 17, the rear extremities of which have secured thereto, by means of angle plates 18^a, beams 18, which extend down over the sides of the 65 ladle when the skimmer is positioned thereon.

To prevent the skimmer from becoming displaced while pouring, a latch bar or analogous member 19 is secured to the angle beams 18, said latch bar being adapted to 70 catch under the lip of the pouring spout of the ladle when the skimmer is applied thereto.

75 As an additional precaution against slipping of the skimmer while pouring, particularly in view of the weight of the slag, kish and the like impurities that may be imposed on the skimmer plate, a further latch member in the form of a bar 20 is provided, said bar being secured to the downwardly projecting beams 18. This latch bar 20 is adapted to engage under a reinforcing band 22 on the ladle 5, note particularly Fig. 3.

80 The skimmer assembly as a whole is adapted to be carried by an overhead crane or auxiliary trolley, and to provide for this method of transportation, a hanger 23 is secured to the side beams 17, said hanger being reinforced by anchor posts 24.

85 The hanger 23 is adapted to receive the auxiliary crane hook for the skimmer apparatus, indicated at 25, and to prevent the skimmer apparatus from turning or becoming displaced angularly while suspended and thus render the positioning operation more difficult, angle plates 26 are secured to the hanger, 95 said angle plates being adapted to bear against said hook 25.

90 The improved skimmer is portable and is adapted to be placed in operative position on the ladle at the time of pouring.

In the operation of the skimmer, the ladle is filled with molten metal from the furnace, the mixer or other source of supply and transferred to its pouring position, and either before moving the ladle or after it has been transferred to pouring position, the skimmer apparatus may be placed in operative position by means of an overhead crane or the auxiliary trolley of the crane carrying the ladle, the latter being a very convenient method. The side of the ladle from which the molten metal is to be poured determines the side on which the skimmer plate is to be placed.

The latch bar 19 is placed under the spout opposite that from which the metal is being poured while the latch 20 is engaged under the band 22. While the skimmer is in suspended position, the positioning operation may be readily performed, the angle plates 26 preventing the skimmer from turning on the crane hook. The skimmer plate 9 should be adjusted to the most effective position, or so that its working edge will prevent the surface inurities from passing off with the molten metal.

After the skimmer is placed in operative position, the ladle is gradually tilted to pour the metal from the spout, the flanged edge of the skimmer engaging the slag, kish and like impurities and holding them back so that they will not pass from the ladle. After the metal has been poured, the impurities may be dumped or otherwise disposed of.

What is claimed as new is:

1. A portable skimmer for use with pouring ladles for molten metal having pouring spouts at diametrically opposite points, said skimmer comprising a supporting frame adapted to be bridged across the top of the ladle and having means cooperating with one of the ladle pouring spouts for retaining the frame in position when said ladle is tilted to pouring position, and a skimmer plate adjustably mounted on said frame for movement into and out of the ladle.

2. A portable skimmer for use with pouring ladles for molten metal having pouring spouts at diametrically opposite points, said skimmer comprising a supporting frame adapted to be bridged across the top of the ladle and having means cooperating with one of the ladle pouring spouts for retaining the frame in position when said ladle is tilted to pouring position, a skimmer plate adjustably mounted on said frame for movement into and out of the ladle, and means for locking said skimmer plate in its adjusted positions.

3. A portable skimmer for use with pouring ladles for molten metal having pouring spouts at diametrically opposite points, said skimmer comprising a supporting frame adapted to be bridged across the top of the metal and having means cooperating with one of the ladle pouring spouts for retaining

the frame in position when said ladle is tilted to pouring position, a shaft fixedly mounted in said frame, a skimmer plate mounted on said shaft and adapted to be rotated about said shaft to adjust said plate relative to said ladle, and means for locking said plate on said shaft.

4. A portable skimmer for use with pouring ladles for molten metal having pouring spouts at opposite sides thereof, comprising a supporting frame having a latch device adapted to engage under one of the spouts of the ladle to prevent displacement of the frame during the pouring operation, and a skimmer plate carried by said supporting frame and adapted to be positioned with its working edge in cooperative relation with the other of said pouring spouts.

5. A portable skimmer for use with pouring ladles for molten metal having pouring spouts at diametrically opposite points, said skimmer comprising an L-shaped frame adapted to extend over the top of the ladle and along the side thereof, and having a latch portion adapted to engage under one of the spouts of the metal to prevent displacement of said frame when the ladle is tilted to pouring position, a shaft carried by said frame, and a skimmer plate journaled on said shaft adapted to be positioned with its working edge in cooperative relation with the spout of the ladle into which the metal is to be poured, and means for locking said skimmer plate against movement relative to said shaft.

6. A portable skimmer of the class specified, comprising a skimmer plate, a supporting frame therefor, a hanger secured to said frame to provide for suspending the skimmer from an overhead crane hook, and angle plates secured to said hanger, said plates being spaced to permit said crane hook to move therebetween, and being adapted to bear against said hook to prevent angular displacement of said skimmer relative to said hook.

In witness whereof, I have hereunto set my hand.

JOHN W. FORSYTHE.
